(57) **ABSTRACT**

A method of removing a bucket from a turbomachine rotor wheel includes exposing a base portion of the bucket, positioning a pulling device radially outwardly of the base portion, connecting the base portion of the bucket to the pulling device through a linking rod, exerting an axially outwardly directed force on the linking rod through the pulling device, and removing the base portion from the rotor wheel.

**METHOD FOR REMOVING A ROTOR
BUCKET FROM A TURBOMACHINE ROTOR
WHEEL**

BACKGROUND OF THE INVENTION

The subject matter disclosed herein relates to the art of turbomachines and, more particularly, to a method of removing a rotor bucket from a turbomachine rotor wheel.

Steam turbines typically include rotating buckets or blades and stationary nozzles. Steam is passed through a number of turbine stages. Each stage includes a row of stationary nozzles and rotating blades mounted to a rotor wheel. Steam expands through the number of turbine stages to rotate rotor wheel creating work.

The buckets are typically mounted to the rotor wheel through a dovetail attachment. The rotor wheel may include an internal, circumferential dovetail. Each bucket or blade has a corresponding dovetail that cooperates with the internal, circumferential dovetail. Generally, each rotor wheel features a loading position or gate opening configured to receive each bucket. Each bucket is mounted to the rotor wheel and manipulated into place about the outer diametric surface. Once all buckets are mounted, a closure bucket is installed in the loading portion and secured to the rotor wheel to prevent bucket liberation.

BRIEF DESCRIPTION OF THE INVENTION

According to one aspect of an exemplary embodiment, a method of removing a bucket from a turbomachine rotor wheel includes exposing a base portion of the bucket, positioning a pulling device radially outward of the base portion, connecting the base portion of the bucket to the pulling device through a linking rod, exerting a radially outwardly directed force on the linking rod through the pulling device, and removing the base portion from the rotor wheel.

According to another aspect of an exemplary embodiment, a method of removing a bucket from a rotor wheel includes positioning a ram radially outward of the base portion, connecting the base portion of the bucket to a ram, exerting a radially outwardly directed force on the base portion, and removing the base portion from the rotor wheel.

These and other advantages and features will become more apparent from the following description taken in conjunction with the drawings.

BRIEF DESCRIPTION OF DRAWINGS

The subject matter, which is regarded as the invention, is particularly pointed out and distinctly claimed in the claims at the conclusion of the specification. The foregoing and other features, and advantages of the invention are apparent from the following detailed description taken in conjunction with the accompanying drawings in which:

FIG. 1 is schematic view of a turbomachine shown in the form of a steam turbine in accordance with the prior art

FIG. 2 is a perspective view of a rotor wheel of the turbomachine of FIG. 1;

FIG. 3 is a perspective view of a closure bucket spaced from the rotor wheel of FIG. 2;

FIG. 4 is a perspective view of the closure bucket of FIG. 3 installed in the rotor wheel;

FIG. 5 is a perspective view of a bucket portion of the closure bucket removed, in accordance with an exemplary embodiment;

2

FIG. 6 is a perspective view of a threaded opening formed in a base portion of the closure bucket of FIG. 5, in accordance with an exemplary embodiment;

FIG. 7 is a perspective view of a pulling device coupled to the base portion of the closure bucket of FIG. 6, in accordance with an exemplary embodiment;

FIG. 8 is a perspective view of the base portion of the closure bucket being removed from the rotor wheel by the pulling device, in accordance with an aspect of an exemplary embodiment; and

FIG. 9 is a perspective view of the base portion of the closure bucket being removed in pieces, in accordance with another aspect of an exemplary embodiment.

The detailed description explains embodiments of the invention, together with advantages and features, by way of example with reference to the drawings.

DETAILED DESCRIPTION OF THE INVENTION

20 A turbomachine is illustrated generally at 2 in FIG. 1. Turbomachine 2 is shown in the form of a steam turbine 4 having a turbine housing 16 that encloses a number of turbine stages three of which are indicated at 20, 21 and 22. Of course, it would be appreciated by one of ordinary skill in the art that 25 the number of turbine stages could vary. Each turbine stage 20-22 includes a corresponding plurality of stationary airfoil members or nozzles, such as indicated at 24 in connection with stage 22, arranged upstream from a plurality of rotating airfoil members or buckets, such as shown at 26. Rotating airfoil members 26 are mounted to a rotor wheel 30 within steam turbine 4.

With this arrangement, steam from a boiler or similar arrangement (not shown) is directed into steam turbine 4. The steam expands through stages 20-22 creating work that is 30 used to power an external component 34. External component 34 may take on a variety of forms including a generator or a pump or other mechanically driven systems. That is, steam turbine 4 could also be used as a power source for a vehicle.

In accordance with the exemplary embodiment illustrated 40 in FIG. 2, rotor wheel 30 includes a rotor wheel body 40 having a first face 42 and an opposing, second face 43 that are joined by an outer diametric surface 45. A bucket receiving slot 60 is formed in outer diametric surface 45. Bucket receiving slot 60 supports plurality of rotating airfoil members 26 about outer diametric surface 45. Bucket receiving slot 60 includes a bucket mounting opening 63 and interior cavity 66 formed in rotor wheel body 40. Each of the plurality of rotating airfoil members 26 includes a base portion 72 (FIG. 3) that supports an airfoil portion 73 and a mounting member 50 or dovetail 74. Airfoil portion 73 includes a ring element 75 that forms part of a circumferentially extending rotor ring 76. Dovetail 74 is shaped to nest within bucket receiving slot 60. Each of the plurality of rotating airfoil members 26 is guided into bucket receiving slot 60 and manipulated into position. 55 Once all buckets are installed, a closure bucket 80 is installed into bucket receiving slot 60 and held in place by mechanical fasteners or grub screws 82 and 84, such as shown in FIG. 4

Over the course of time, steam turbine 4 may be taken 60 offline for maintenance and/or repair. Maintenance includes an inspection of the buckets. During operation a bucket(s) may become damaged. The damaged bucket(s) is removed and replaced. Removing the damaged bucket first requires removal of the closure bucket 80 which may, itself, be damaged. In accordance with an aspect of an exemplary embodiment, removal of a damaged closure bucket 80 includes removing grub screws 82 and 84 and airfoil portion 73, as 65 shown in FIG. 5, to expose an upper surface 90 of base portion

72. After removing airfoil portion 73, a bore 96 is formed in closure bucket 80, as shown in FIG. 6. Bore 96 extends radially inwardly into base portion 72. A plurality of threads 100 are formed in base portion 72 along bore 96.

After forming threads 100, a pulling device 110 is arranged radially outward of closure bucket 80, as shown in FIG. 7. Pulling device 110 includes a base 112 supported by rotor ring 76 and a ram 114. Pulling device 110 may rely upon air pressure, hydraulic pressure, or electrical current to operate ram 114. Ram 114 is connected to base portion 72 through a linking rod 120. Linking rod 120 includes a plurality of threads (not separately labeled) that engage with threads 100 in base portion 72. Ram 114 is actuated to exert a radially outwardly directed force on base portion 72 through linking rod 120. The radially outwardly directed force may cause base portion 72 to release from rotor wheel 30, as shown in FIG. 8. At this point, the remaining buckets may be circumferentially shifted to bucket mounting opening 63 and removed from rotor wheel 30 for inspection and/or replacement.

At this point it should be understood that the exemplary embodiments describe a method for removing a closure bucket from a rotor wheel. In the event that the closure bucket may does not release from rotor wheel, base portion and pin may be broken up into a plurality of pieces, indicated generally at 140, and removed, as shown in FIG. 9. At this point, the remaining buckets may be circumferentially shifted to bucket mounting opening 63 and removed. If the additional buckets resist removal efforts, all airfoil portions may be removed and corresponding base portions broken up into pieces 140 to enable removal. It should also be understood that while described in terms of removing a bucket from a rotor wheel in a steam turbine, the method may also be employed to remove buckets from rotor wheels arranged in other turbomachine systems including compressors and gas turbines. Further, it should be understood that the method may be used to remove the closure bucket without requiring that the rotor wheel be separated from other rotor wheels or removed from the turbine rotor. The destruction of a single bucket, *in situ*, reduces downtime and overall maintenance costs associated with the steam turbine 4.

While the invention has been described in detail in connection with only a limited number of embodiments, it should be readily understood that the invention is not limited to such disclosed embodiments. Rather, the invention can be modified to incorporate any number of variations, alterations, substitutions or equivalent arrangements not heretofore described, but which are commensurate with the spirit and scope of the invention. Additionally, while various embodiments of the invention have been described, it is to be understood that aspects of the invention may include only some of the described embodiments. Accordingly, the invention is not to be seen as limited by the foregoing description, but is only limited by the scope of the appended claims.

What is claimed is:

1. A method of removing a bucket from a turbomachine rotor wheel, the method comprising:
exposing a base portion of the bucket, wherein exposing the base portion of the bucket includes removing an airfoil portion from the base portion;
positioning a pulling device radially outwardly of the base portion;
connecting the base portion of the bucket to the pulling device through a linking rod;
exerting a force on the linking rod, the force being exerted through the pulling device, the force being directed radi-

ally outwardly of the rotor wheel, the force forcing the linking rod radially outwardly from the rotor wheel into the pulling device; and
removing the base portion from the turbomachine rotor wheel.

5 2. The method of claim 1, wherein connecting the base portion of the bucket includes forming a bore into the base portion.

10 3. The method of claim 2, further comprising: forming a plurality of threads along the bore.

4. The method of claim 1, wherein positioning the pulling device includes supporting the pulling device on a rotor ring surrounding the turbomachine rotor wheel.

15 5. The method of claim 1, wherein positioning the pulling device includes supporting a ram radially outwardly of the base portion.

6. The method of claim 1, wherein exerting the radially outwardly directed force includes directing a hydraulic fluid into the pulling device.

20 7. The method of claim 1, wherein exerting the radially outwardly directed force includes operating a screw in the pulling device.

25 8. The method of claim 1, wherein removing the base portion further comprises:

breaking the base portion into multiple pieces; and
removing each of the multiple pieces from the turbomachine rotor wheel.

9. A method of removing a bucket from a rotor wheel comprising:

30 exposing a base portion of the bucket, the exposing including removing an airfoil portion from the base portion;
positioning a ram radially outwardly of the bucket;
connecting a base portion of the bucket to the ram;
exerting a radially outwardly directed force on the base portion, the exerting the radially outwardly directed force on the base portion includes forcing a linking rod radially outwardly from the rotor wheel into the ram; and
removing the base portion from the rotor wheel.

40 10. The method of claim 9, wherein connecting the base portion of the bucket includes forming a bore into the base portion.

11. The method of claim 10, further comprising: forming a plurality of threads along the bore.

45 12. The method of claim 11, wherein connecting the base portion to the ram includes establishing a threaded connection between the ram and the plurality of threads.

13. The method of claim 9, wherein positioning the ram includes supporting the ram on a rotor ring surrounding the rotor wheel.

50 14. The method of claim 9, wherein forcing the linking rod radially outwardly includes directing pressurized fluid into the ram.

15. The method of claim 14, wherein directing a pressurized fluid into the ram include urging hydraulic fluid into the ram.

55 16. The method of claim 9, wherein exerting the radially outwardly directed force includes directing an electrical current to the ram.

17. The method of claim 16, wherein the electrical current powers a screw.

60 18. The method of claim 9, wherein removing the base portion further comprises:

breaking the base portion into multiple pieces; and
removing each of the multiple pieces from the rotor wheel.
